TUBE CLOSING SYSTEM

Hans Kissling, St. Martin, Switzerland

Application July 14, 1949, Serial No. 104,611
In Switzerland July 15, 1948

7 Claims. (Cl. 222—521)

1

The present invention relates to closure means in particular adapted for collapsible tubes which have a neck portion with external screw threads. Such neck portion has a central opening for the discharge of the contents of the tube or like receptacle.

It is one of the principal objects of this invention to provide means affording closing of a tube of the aforesaid type and sealing the latter substantially hermetically and in a very quick and efficient manner.

It is another object of the invention to provide means considerably reducing the manufacturing price of closure means as compared with the conventional closure devices now in use.

Still another object of the present invention is to provide means ensuring interchangeability of heretofore used closure caps with closure means made in accordance with this invention, whereby the usefulness, saleability and safety of collapsible tubes will be greatly enhanced.

To accomplish these and other objects the closure device according to the invention is provided with an insert, which assumes the shape of a hollow cylinder which partially protrudes into the neck of the collapsible tube or container and has inwardly extending arms connecting the latter with a plug portion forming part of the insert.

According to the invention the closure means are so constructed that the aforesaid insert is adapted to telescopically engage a cap, said cap and said insert being provided with respective seats or contact surfaces lying in different planes with respect to each other, whereby said seats are brought in engagement with each other successively.

Other important objects and advantages of the invention will appear hereinafter as the description of the invention progresses.

The attached drawings show, by way of example, preferred embodiments of the invention.

In the drawings:

Fig. 1 is a vertical sectional view through the neck of a container or tube with a closing system applied thereto and shown in partly closed position and made in accordance with the invention;

Fig. 2 is a top plan view of the insert forming part of the closing system shown in Fig. 1;

Fig. 3 is a vertical sectional view of a closing system in modified form and seen in closed position similar to that illustrated in Fig. 1;

Fig. 4 is a top plan view of the insert forming part of the closing system shown in Fig. 3; and

2

Figs. 5 and 6 show the closing system of Figs. 1 and 3, respectively, in fully open position.

Referring now more particularly to the drawings, there is disclosed the neck of a tube or similar container 1 having the outer threads 21 with which is movably engaged a cap member 2 having inner threads 9. Cap 2 embraces a fitting or insert member 3 having a portion 4 for the insertion into the neck 1 of the container.

Cap 2 and insert 3 are preferably made of thermoplastic material, e. g. polystyrene. The fitting or insert 3 includes the lower portion 4 assuming the shape of a hollow cylinder which is held in place in the tube neck 1, e. g. by having it introduced in the interior of the neck 1 whereby the screw threads 21 are tapped on the latter while a mandrel is introduced into the portion 4 of the fitting. An intermediary part 5 forming a shoulder or flange rests on the upper or end edge 16 of the tube neck 1, the part 5 being further connected to an upper hollow cylindrical portion 6 of larger diameter than that of the lower portion 4. Arms 7 extend from shoulder 5 and portion 6 toward the center of hollow insert 3 and upwardly therewithin and terminates in a plug member 8. The aforesaid parts 4 to 8 are made from a single piece of material, as may be visualized from Fig. 1 of the drawing.

On the inside of the closing cap 2 are provided inner threads 9 engaging with slight clearance the threads 21 on the tube neck 1, a cylindrical surface 10 adapted to slide with a reduced clearance over the outer surface of the portion 6 of the fitting 3, a conical surface 11 having an apex angle of about 90° and a central opening 13 defined by the cylindrical surface 12.

When closed, the annular narrow portion 14 of the conical surface 11 adjacent to the central opening 13 cooperates with a narrow corresponding seat surface 15 on the plug 8. Another narrow annular portion 16 of the conical surface 11 of the cap, located adjacent to the cylindrical surface 10 cooperates with a narrow seat 17 on the end or upper surface of the portion 6 of the fitting 3. Seats 15 and 17 are disposed on respective planes different from each other, as the seat 17 is shifted somewhat inwardly in a direction perpendicular to the conical surface 11 by a distance a , whereby when closing the tube or container the annular portion 14 comes immediately into engagement with its seat 15 and prior to the engagement of annular portion 16 with its corresponding closure seat 17, which latter engagement takes place only after the cap 2 has been screwed home by a further smaller amount

50

55

on the neck of the tube 1 so as to produce a slight elastic deformation of said cap bearing on both seats. The inside of the tube is thus hermetically sealed both with reference to the central opening 13 and to the threads 9. Furthermore, the upper cylindrical portion 18 of the plug 8 engages the central opening 13 of the cap 2 so as to close it completely and, finally, the top surface 19 of the closing cap 2 and the top surface 20 of the plug 8, i. e. of its upper portion 18, become substantially flush with each other. Thus, any excess of the tube contents may easily be wiped off at said flush end surfaces 19, 20. When closing the tube, its contents are urged away from the surface 10 of the cap through the cooperating portion 6 of the fitting, so as to prevent them from reaching the threads 9 and soiling same. Referring now specifically to Figs. 3 and 4, there is shown a modified form of the tube closing system according to the present invention, wherein the inclined seats 15, 17 and plug 8 of Figs. 1 and 5 are replaced by cylindrical seats 15a, 17a, which are arranged transversely of the plug 8a and engage complementary surfaces 14a and 16a arranged transversely of the cap 2a and adjacent the inner and outer ends of the conical wall surface 11a.

It is apparent that this modified closing system of Figs. 3, 4 and 6 operates in a manner similar to that of the device of Figs. 1, 2 and 5, as was previously described in detail.

The closure seats 15a and 17a of the insert 3a in this latter embodiment cooperate, respectively, with the engageable sealing means or surfaces 14a, 16a which are substantially cylindrical in cross section and are positioned on the inner wall of the cap 2a. The vertical distance between seat 15a and the corresponding sealing surface 14a is shorter than the vertical distance between seat 17a and its corresponding sealing surface 16a; this difference being indicated by the letter b in Fig. 3.

Since the insert 3a is provided with plug 8a, it is well understood that the latter engages the opening 13a of cap 2a upon engagement of closure seat 15a with its corresponding engageable means 14a and prior to the engagement of the other closure seat 17a with its corresponding engageable means or surface 16a.

In brief, it may be stated that either of the above described closing devices provides a perfectly tight closure at all points when in closed position, even after long use and without the formation of any corrugations when the tube contains granular material, despite the fact that the closure seats are relatively narrow.

Uppermost surface 20a of cylindrical portion 18a of plug 8a is flush with surface 19a of cap 2a in such closed position.

An absolutely tight and durable closure is afforded by the fact that the screw connections 9, 21 and 9a, 21a between the tube neck and the cap are sealed against the tube contents. Thus the possibility is avoided that the contents will dry between the screw threads and would hinder a complete closing of the tube or container. The manufacturing price of the new closing system made in accordance with the invention is not higher than the conventional closure devices heretofore in use. The above advantageous features distinguish the device substantially from all tube or container closing means on the market up to date.

While several embodiments of the invention are described hereinabove, it is to be understood that

the scope of the invention is not limited to the very structure shown and disclosed in the drawings and that modifications and rearrangements of the several parts of which the device consists 5 will fall within the purview of the accompanying claims.

Having thus described the invention, what is claimed as new and desired to be secured by Letters Patent is:

- 10 1. A closure structure for application to a dispensing container having a neck, comprising a hollow insert for engagement with said neck, said insert being provided with a first closure portion and a second closure portion, respectively, said closure portions being spaced apart from each other, and a cap member embracing said insert and arranged for movement relative to said neck, said cap member being provided with an inner closing surface, said closing surface terminating in and defining an opening in said cap member, said closure portions being seated on said insert on different planes so that upon movement of said cap member into one position relative to said neck said first closure portion 15 engages said closing surface prior to the engagement of said second closure portion with said closing surface, said insert being adapted to conduct contents from within said container through said neck for dispensing purpose to said opening of said cap member when the latter is in another position relative to said neck.
- 20 2. A closure structure according to claim 1, wherein one of said closure portions of said insert is substantially cylindrical in cross-section, 25 the other of said closure portions being conically shaped, said closing surface being substantially conical and terminating in a cylindrical part at a location opposite said cylindrical closure portion of said insert.
- 30 3. A closure structure for application to a dispensing container having a neck, comprising a hollow insert for position in and engagement with the end of said neck, said insert including a first closure seat portion and a second closure 35 seat portion, respectively, said closure seat portions being spaced apart from each other and arranged on said insert at two different planes, and a hollow cap member for embracing said insert and arranged for movement relative to said neck, 40 said cap member being provided with a dispensing opening and with an inner closing surface extending toward said opening, said closing surface being conical in shape and extending within said cap member substantially opposite 45 said closure seat portions of said insert, so that upon movement of said cap member in one direction of said neck said first closure seat portion engages said closing surface prior to the engagement of said second closure seat portion 50 with said closing surface, said hollow insert being adapted to conduct contents from within said container through said neck to said opening of said cap member when the latter is moved in another direction relative to said neck.
- 55 4. A closure structure according to claim 3, wherein said hollow insert is provided with a plug member disposed centrally of said insert, said plug member being provided with said first closure seat portion, said insert further including a substantially tubular portion terminating in an end bearing said second closure seat portion at a level different from that of said first closure seat portion.
- 60 70 5. A closure structure for application to a dispensing container having a neck with a wall

surface; comprising a cap member adapted for movably engaging said neck and provided with an inner wall surface, an inclined inner wall surface connected to said inner wall surface and defining a cap opening, a hollow insert for engagement with said wall surface of said neck and with said inner wall surface of said cap member, and first and second seats, respectively, on said insert and extending thereon in different planes with respect to each other, said first and second seats being successively engageable with corresponding locations of said inclined wall surface upon movement of said cap member toward said neck for first sealing said opening of said cap member and for then causing said insert to firmly engage with said neck of said container by means of said cap member.

6. The combination, in a closure structure for containers, of two telescopically movable hollow members, with spaced apart closure seats arranged on one of said members and in different planes with respect to each other, and engageable means for said closure seats on the other of said members and positioned for successive engagement of said closure seats upon movement of said one member toward the other member, one of said members having an opening for dispensing purposes, the other of said members terminating in a plug insertable in said opening upon engagement of one of said closure seats prior to the engagement of the succeeding seat for sealing said container.

7. The combination, in a closure structure for a container having inner and outer walls, of two telescopically movable hollow members, with spaced apart closure seats arranged in two different planes with respect to each other and

disposed on one of said members, and engageable means for cooperation with said closure seats, respectively, and positioned on the other of said members, said one member forming an insert provided with a portion adapted to engage with said inner wall of said container, the other member forming a cap constructed for movable engagement with said outer wall of said container and embracing said insert, said closure seats being cylindrical in cross section and being so arranged on said insert that the vertical distance between one of said closure seats and its corresponding engageable means is shorter than the vertical distance between the other closure seat and its corresponding engageable means, whereby said closure seats engage successively with the respective engageable means when said cap is moved on said outer wall relative to said insert, said cap having an opening for dispensing purposes, said insert being provided with a plug insertable in said opening upon engagement of said one closure seat with its corresponding engageable means and prior to the engagement of the other closure seat with its corresponding engageable means.
